(57) **CLAIM**

The ornamental design for a sectional sofa, as shown and described.

DESCRIPTION

FIG. 1 is a front, left, top perspective view for a first embodiment of a sectional sofa according to my new design.

FIG. 2 is a front view of the sectional sofa of FIG. 1.

FIG. 3 is a rear view of the sectional sofa of FIG. 1.

FIG. 4 is a right side view of the sectional sofa of FIG. 1.

FIG. 5 is a left side view of the sectional sofa of FIG. 1.

FIG. 6 is a top view of the sectional sofa of FIG. 1.

FIG. 7 is a bottom view of the sectional sofa of FIG. 1.

FIG. 8 is a front, left, top perspective view for a second embodiment, showing a portion of a sectional sofa according to my new design.

FIG. 9 is a front view of the portion of a sectional sofa of FIG. 8.

FIG. 10 is a rear view of the portion of a sectional sofa of FIG. 8.

FIG. 11 is a right side view of the portion of a sectional sofa of FIG. 8.

FIG. 12 is a left side view of the portion of a sectional sofa of FIG. 8.

FIG. 13 is a top view of the portion of a sectional sofa of FIG. 8.

FIG. 14 is a bottom view of the portion of a sectional sofa of FIG. 8.

FIG. 15 is a front, left, top perspective view for a third embodiment, showing of a portion of a sectional sofa according to my new design.

FIG. 16 is a front view of the portion of a sectional sofa of FIG. 15.

FIG. 17 is a rear view of the portion of a sectional sofa of FIG. 15.

FIG. 18 is a right side view of the portion of a sectional sofa of FIG. 15.

FIG. 19 is a left side view of the portion of a sectional sofa of FIG. 15.

(Continued)

FIG. 20 is a top view of the portion of a sectional sofa of FIG. 15; and,
 FIG. 21 is a bottom view of the portion of a sectional sofa of FIG. 15.

The broken lines illustrate portions of the sectional sofa and form no part of the claimed design.

1 Claim, 21 Drawing Sheets
